UNITED STATES PATENT OFFICE.

JOSEPH A. GROEBLI, OF NEW YORK, N. Y.

CLOTH-REELING DEVICE FOR EMBROIDERING-MACHINES.

1,116,693.

Specification of Letters Patent.

Patented Nov. 10, 1914.

Application filed July 11, 1911. Serial No. 638,308.

To all whom it may concern:

Be it known that I, JOSEPH A. GROEBLI, a citizen of the United States, and a resident of the city, county, and State of New York, have invented a certain new and useful Fabric-Reeling Device for Embroidering-Machines, of which the following is a specification.

In large embroidering machines, wherein the fabric is carried upon a tambour frame which is moved after each stitching operation of the machine, the fabric, usually of two separate pieces, is usually supplied in such quantities that, when one or more rapport rows of embroidery has been worked upon each piece of fabric, the fabric can be reeled up sufficiently to bring new portions of the fabric before the rows of needles, to be acted upon. For holding the fabrics longitudinal rollers have been employed which extend nearly the length of the machine and which are adapted to hold a proper supply of fabric; and by turning the rollers the fabric is reeled from one to the other, generally from the lower to the upper, sufficiently to move the embroidered portion of the fabric away from the needle row and to bring a new portion into operative relation thereto. Usually the fabric rollers are duplicated, one set of parallel rollers supporting a piece of fabric for one row of needles, and another set supporting a second piece for the second row of needles, the two sets being arranged in vertical parallelism. In order to preserve the fabric taut for the embroidering operation it is necessary to reel the fabric tight between the rollers; and by reason of the great length of the rollers they have a tendency to sag at their middle, distorting the fabric, which tendency is overcome by providing supporting brackets for the rollers near the middle. Aside from the tension placed upon the fabric by the rollers it is necessary to employ stretchers which are located near each end of the machine and which engage the fabric and stretch the same in opposite directions. So that the fabric is drawn taut in four directions by oppositely and horizontally and vertically acting devices to keep it taut to prevent vibration and to make the embroidering possible.

Under the present methods of operating embroidering machines it requires a great deal of time and labor to reel the fabric each time the needles have completed the

stitching of a rapport row of embroidery; and the time occupied in this reeling and adjusting operation is out of proportion to the time required to actually stitch the embroidery, and in fact, materially affects the total output of the machine. Each time the machine has completed a row or rows of embroidery and a new portion of the fabric is to be reeled into place several laborious operations have been necessary, all of which were heretofore done manually and had to be done in successive order, so that the operations could not be materially speeded by dividing the work among a greater number of attendants.

When a change of fabric is made, several operations are necessary and have to be performed in a given order. The devices which engage the side of the fabric at each end of the machine are first released; the intermediate roller supporting brackets are then released to permit the roller to be turned; the lower or upper rollers of each set are then released to take the tension off the fabric; the roller (usually the upper) of each set is then turned to reel up enough fabric to present a new surface for embroidering; the lower rollers are again tightened and the supporting brackets adjusted; and finally the side tighteners are inserted and tightened. Aside from the labor necessary to perform these operations and the cost of it, the machine must remain idle while the reeling operations take place.

The objects of my present invention are, to provide mechanism by which any one or all of the above operations may be accomplished mechanically, thereby avoiding the manual labor; decreasing the time required for the operations; and performing the operations more uniformly and exactly in every respect. This increases the output of the machine and decreases the cost of production and improves the quality of the product by making the whole machine more uniform in its many functions.

To carry out my invention I provide mechanism which will mechanically perform the above functions, but which is preferably, though not necessarily, mechanically controlled. The mechanism in the fullest embodiment of my invention, automatically performs the several operations in such relative order, that there will be no conflict in the operations and so that a uniform tension is placed on the stretched fabric. In em-

ploying all the features of my invention it is possible to predetermine and adjust the amount of tension which will be placed on the fabric, with due regard to the character 5 of the material which is being used. Naturally a light net fabric will neither stand, nor require, as much tension as a heavy cotton fabric and proper adjustment must therefore be made for different fabrics.

10 I preferably distribute the power to the several branches of the mechanism from a common source. As the tambour frame is adapted to be moved in any direction in its plane, and its movements should not be materially impeded, I mount the mechanism for 15 performing the several functions upon the tambour frame, to move therewith, and I transmit the power thereto by flexible means, whereby there will be no interference 20 with the movements of the tambour frame. In carrying my invention to its higher development I prefer to operate the corresponding devices for performing the several functions, in synchronism with each other, 25 and to distribute the operating forces to both ends of the machine in order to have all parts move smoothly.

In the drawings forming a part of this application Figure 1, is a rear elevation of 30 an embroidering machine, showing only such parts thereof, as are necessary to teach the application of my invention, in which view the greater part of my improvements are shown. Fig. 2, is an enlarged elevation 35 with parts broken away, showing various controlling and operating parts of the mechanism. Fig. 3, is a sectional view showing the device for turning the rollers for reeling the fabric. Fig. 4, is a sectional view showing 40 the device for placing the tension on the sides of the fabric, generally referred to as side clamps. Fig. 5, is a sectional view showing the supporting brackets placed near the middle of fabric rollers, and 45 adapted to prevent sagging of the rollers and prevent distortion when the fabric is reeled taut, Fig. 6, is a sectional view showing parts forming a continuation of the upper part of Fig. 5, and also Fig. 3, Fig. 7, is 50 an elevation of the belt shipper which controls the starting and stopping of the various mechanisms, Fig. 8, is an elevation of the mechanism for controlling the direction 55 of operation of the several mechanisms, Fig. 9, is a face view of the cam for operating the side tension devices, Fig. 10, is a face view of the cam controlling the mechanism which turns the fabric rollers, Fig. 11, 60 is a sectional view taken on the line 11—11 of Fig. 2, Fig. 12, is a sectional view taken on the line 12—12 of Fig. 4, showing the side clamping rollers, Fig. 13, is a sectional view taken on the line 13—13 of Fig 2, Fig. 14, is an elevation of a modification of certain parts, by which some of the mechanism

may be thrown out of operation, Fig. 15, is a view showing means for throwing one of the fabric rollers out of operation, Fig. 16 is a face view showing the cam which operates the brackets and the device for placing tension on the fabric between the rollers. 70

I have shown a stationary embroidering machine frame consisting of end standards 1 and 2, at opposite ends of the machine, connected by longitudinal beams 3 and 4, arranged one above the other in the usual manner. Upon this stationary frame most of the embroidering mechanisms are mounted and the frame varies in practice, but my invention in no way interferes with the ordinary construction of the stationary frame. 75

Arranged to move in a vertical plane, is a tambour frame, consisting of the longitudinal bars 5 and 6 forming the top and bottom of the frame, which are connected by 80 the end bars 7 and 8, the four bars forming the ordinary movable tambour frame of the embroidering machine which is subject to movement in any direction in its vertical plane. I have shown a counter balancing mechanism of approved type in the lower part of Fig. 1. This consists of the angle levers 9 and 10, fulcrumed on the studs 11, and 12, at opposite ends of the machine and the arms 13, of which levers are provided 85 with rollers 14, upon which the tambour frame is supported. The arms 15, of these levers extend upwardly and are connected by a longitudinal strap or rod 16 which causes, the angle levers, to act in unison and 90 to raise and lower both ends of the tambour frame alike. 100

On an arm 17 of one of the angle levers, I have provided a weight 18, which counterbalances, through the parallel motion device, the tambour frame. All of these parts are of well known construction and other known embroidering machines may be provided with my present invention. 105

The above parts constitute the principal elements of an embroidering machine, but it will be understood that there are many mechanisms used to perform the embroidering operations, none of which need be here shown; and in so far as my present invention is concerned any means may be employed to move the tambour frame such as a pantograph or a jacquard. 110

Upon the tambour frame I have mounted various shafts and working parts which are carried by the tambour frame but which in no way interfere with its operation. Preferably along the top of the tambour frame I provide horizontal shafts 19, 20 and 21, 115 which I have arranged in substantially superimposed relation and which serve to distribute the operating force through the machine so that the duplicate mechanism on each end of the machine will be operated 120 uniformly and evenly. 125

In describing in detail the various devices for carrying out the several operations, I will follow the order in which the different devices operate, in so far as it may be practicable to do so.

I have shown my invention as used on a machine wherein two different pieces of fabric 22 and 23 are carried upon the tambour frame; as it is the general practice to 10 employ the two pieces of fabric, though it will be apparent that my invention is not limited to use in such a machine. The upper fabric is supported upon a pair of horizontally disposed rollers 24 and 25, which 15 are so disposed upon the tambour frame as to expose a portion of the fabric between them, before a row of needles in the usual manner. The rollers are revoluble in the journals 26, at each end and are carried by 20 the movable tambour frame. A second set of rollers 27 and 28, is likewise mounted below the first; and in a position to expose the fabric stretched between them before the lower row of needles in the usual manner. 25 There are thus provided two sets or pairs of rollers which are usually alike in all respects and perform the same function. It is with the condition of the fabric between the rollers of each pair that my invention principally has to do.

When the fabric is first supplied to the rollers usually a quantity is placed around the lower roller of each pair and the top end of the fabric is connected with the upper roller of each pair; and when the fabric between the rollers has been operated upon by the sewing mechanisms the fabrics are reeled off the lower rollers and onto the upper rollers and are finally removed when 40 all the fabric has been provided with embroidery. Usually the edges of the fabric which come near the ends of the rollers are called the sides and I will so refer to them in the following description. The revolving 45 of these fabric rollers, to reel the fabric as well as the operation of their locking and incidental devices, have usually been done by manual labor but in my present invention this is accomplished by mechanically operated mechanism.

I have provided preferably at opposite ends of the machine, the upright shafts 29, which are revolved by the horizontal shaft 20, through the miter gears 30 and 31 connected with the respective shafts. Upon the upright shafts I have provided the worms 32, which mesh with the worm gears 33, on the ends of the upper fabric rollers of each set; and through this connection the 55 upper rollers are revolved to reel the fabric from the lower to the upper rollers in case the movement of the fabric is to take place in such direction. The worms 32, generally revolve with the shafts 29, but are capable of 60 slipping on them.

On each shaft 29, I have provided a collar 34, which can be adjusted in its position through the bolt 35, and between this collar and the worm 32, I have provided a spiral spring 36, which permits, but resists, 70 the movement of the shaft 29 inside the worm. When the shaft 29, is revolved, therefore, the worm 32, acting on the worm gear 33 will revolve the upper roller of the pair, until the tension in the fabric overcomes the friction of the spring 36, when the further revolution of the shaft 29, will 75 no longer revolve the worm 32, because there will not be sufficient friction between the collar 37, and worm 32. The amount of friction between the worm 32, and collar 37 and therefore the limit of stress which will be placed upon the fabric in the reeling operation, is adjusted by moving the collar 34, to place more or less stress on the spring 36, 80 and therefore more or less friction between the worm and the collar 37 against which the spring presses the worm. I have also provided means for revolving the lower roller of each pair simultaneously with the 85 upper rollers, but I prefer to make a difference in the lower roller's operation, so that a partial releasing of the lower roller can be made before the reeling operation takes place, so as to relieve the tension on the fabric. 90 On the same shafts 29 I have shown the worms 38, which mesh with the worm gears 39 of the lower roller and through the same the lower rollers are revolved simultaneously with the upper roller and in the 100 same direction of movement. The worm 38, however, is movable longitudinally to a slight extent on the shaft 29, and to permit this the worm is secured to the shaft by a feather 41, in the shaft (see Fig. 3). 105 The worm therefore revolves with, but is movable longitudinally along, the shaft. This is duplicated for the lower roller of the second pair if two pairs of rollers are employed and the worms for all four rollers 110 are preferably mounted on the two shafts 29, at each end of the machine. I prefer to employ a shaft 29 at each end of the machine to reduce the torsional strain on the fabric rollers.

The worm 32 and gear 33 are preferably of greater pitch than the worm 38, and gear 39, so that when the shaft 29 is revolved, the upper roller of each pair will be revolved somewhat faster than the lower 120 roller, until the tension of the cloth becomes too great, in which event the worm 32, will slip. The reason for this difference in pitch is that the amount of fabric on the upper and lower rollers will not always be the same and if the rollers are turned at the same speed there may at times be an undesirable slack cast in the fabric between the rollers if the upper roller should have less fabric than the lower one, owing to the dif- 130

ferences in the diameter of the fabric on the rollers. Upright rods 42, are mounted to move vertically in their bearings 43, in the tambour frame, and they are preferably disposed near the shafts 29. These bars carry arms 44, one for each of the worms 38, which engage against the lower end of the lower worms 38, and retain the latter in the position shown in Fig. 3. The rods are moved up and down at certain times to cause the worms 38 to revolve the lower rollers at certain times. This is in addition to the movement caused by the shaft 29, and is independent thereof, so that such additional movement may be independently controlled. Each of the rods 42, carries an arm 45 (see Fig. 6) on its upper end in which turns a threaded portion 46 of the shaft 47. The shaft 47 revolves in the journals 48, in the tambour frame and there is provided thereon a collar 49 and a collar 50 between which is a coiled spring 51. Above each collar 50, is a miter gear 52, loose on the shaft, and this gear frictionally engages with the collars 50, and 50^a. By adjusting the collar 49, through the bolt 53, the tension of spring 51, may be adjusted to determine the resistance which the miter gear 52, must overcome before slipping between collars 50 and 50^a. The gear 52 miters with gear 54, on one of the longitudinal shafts, preferably the uppermost one 21, of the series; and the shafts 47 at each end of the machine thus receive their operating force. When the shafts 47 are revolved, the bars 42 are raised or lowered, according to the direction of rotation of the shaft, and the reciprocative movement of the worms 38 causes the lower set of rollers to be revolved in one direction or the other, thereby tightening or loosening the fabric. I prefer to place the final vertical tension on the fabric in this way and similarly to release the lower rollers before the reeling operation takes place.

The device for operating the intermediate brackets for rollers is as follows: I have shown a bar 55 connected at top and bottom, rigidly to the upper and lower horizontal bars 6 and 5, of the tambour frame and this supports two of the brackets, 56 and 57, which I prefer to make rigid. These curved brackets 56 and 57 engage over the lower roller of each pair, or the fabric which is reeled thereon, and prevent the tension of the fabric from distorting the rollers, between their ends. These brackets need not be moved by the operating mechanism, but they can be adjusted by the bolts 58, to the required position. The brackets which engage under the upper roller of each set I prefer to make subject to a raising and lowering device. I have provided an upright bar 59 upon which are provided the curved brackets 60, which engage under the

middle portion of the upper rollers of the two pairs, or under the fabric, on the rollers, and the bar is adapted to be moved up or down by suitable mechanism. For raising and lowering the bar 59 I preferably employ the same kind of device as is used to operate the rod 42 and which is shown in Fig. 6. The bar 59 has a journal in which the threaded end 46, of a shaft 47 turns, and this shaft is provided with the same elements and operates in the same way as the shaft 47 of the previous description. The miter gear 52 on this shaft is operated preferably by the miter 60 on the same shaft 21, that operates the shafts 42. By utilizing the longitudinal shaft 21, for the bracket mechanism fewer parts are required. The raising of the bar 59, and therefore the brackets 60, causes the upper rollers to be supported in their intermediate portion, thereby preventing sagging of the rollers and slackness or distortion of the fabric. The lower rollers are not necessarily provided with brackets engaging under them, because the fabric itself, when under proper tension prevents sagging of the lower rollers; and in fact the support of the lower rollers is more or less taken up by the brackets 60, by reason of the fabric. It should be here noted that to the shaft 47 is secured an arm 61, which is engaged by the journal 45 when the bar 59 or 42 as the case may be has been lowered as far as required, and if the gear 52, is revolved after this engagement takes place there will be a slipping action between the gear 52, and the collar 50, so that the shaft 47, will not revolve beyond the extent required to lower the bar 59 or 42, the required amount, a maximum suitable for all occasions.

The next branch of the mechanism relates to the device for placing the longitudinal stress upon the fabric, and consists of means at each end of the machine for engaging the fabric and exerting stress in opposite directions. Preferably near each end of the tambour frame I provide an annularly grooved roller 62, which is journaled between brackets 63 at each end thereof and the roller is free to revolve upon its bearings. The brackets 63, are carried on a shaft 64, fulcrumed in stationary brackets 65 on the tambour frame and the brackets 63 are so shaped and disposed, as to bring the roller 62, on the rear side of the fabric which is stretched between the pair of fabric rollers; and I prefer to dispose the roller 62, between the fabric rollers of each pair. A pin roller 66 is journaled in the brackets 67, of the tambour frame, wherein the roller is free to be revolved. This pin roller is disposed on the opposite side of the fabric from the roller 62, and therefore preferably on the front side thereof. The pin roller is provided with tangentially disposed pins 68, 130

inclining forward in the direction of the roller's rotation and these pins are disposed in line with the grooves 70 of the roller 62, so that when the pin roller is revolved the 5 pins are adapted to pass into the grooves 70 of roller 62, passing through the fabric as they do so. The shaft 71, of the pin roller is provided with a cam 72 and the shaft 64, of the grooved roller is provided with an 10 arm 73 having a roller 74 which engages in the groove 75, of the cam, and when the shaft of the pin roller is oscillated to engage or disengage the pins with the fabric the cam 72 acting on the arm 73, rocks the 15 shaft 64, and moves the grooved roller 62, toward or from the pin roller, to coöperate in the engaging or disengaging of the fabric. There is a plate 76 mounted near the pin 20 roller which forms a sort of comb and the slots 77, of this comb are in line with the pins 68. When the grooved roller presses the fabric into contact with the periphery of the pin roller and the latter is revolved to the left in Fig. 12, the frictional contact between 25 rollers 62, and 66 will place the fabric under tension and then the pins 68 pass through the fabric and into the grooves 70, of the grooved roller 62, and the pin roller continues to turn until the proper lateral 30 stress has been placed on the fabric in the longitudinal direction of the machine. When the fabric is to be released, the roller 62, is swung out on the arms 63, and the roller 66 is revolved reversely to its previous 35 movement, when the pins 68 will pass through the slots of the comb 76, and disengage from the fabric which will thus release the end clamping device from the fabric, to permit of the reeling operation of the fabric rollers. The grooved roller 62, is free to revolve with the pin roller under frictional contact therewith. The shaft 71, of the pin roller extends upward, passing 40 through a suitable journal in the tambour frame, and is provided with a gear 78 which 45 mites with a gear 79, on the lowermost longitudinal shaft 19, from which latter the shaft 71 receives its operating force.

The side tension mechanism just described 50 is duplicated at the opposite end of the machine, but it is arranged to operate in a reverse direction, so that the pin roller on the right will pull on the fabric in the opposite direction to that on the left. Likewise the 55 same will preferably be duplicated for the fabrics of both pairs of rollers.

So far the mechanisms for operating the fabric rollers, for operating the roller brackets, and for operating the side clamps have 60 been traced back to the longitudinal operating shafts; and I will now describe the mechanism by which the latter are operated and controlled. While the power for operating the several longitudinal shafts is 65 preferably received from a source independ-

ent of the tambour frame, I preferably mount the means for controlling the operations of the shafts on the tambour frame. I have provided means for predetermined the extent of the reeling operation of the fabric 70 rollers, which means can be set to cause the same to operate any desired amount, and when the means are so set the movement may be initiated by the operator; and the mechanism will automatically stop when the 75 various operations have been completed.

Upon the end of, and to the middle of the upper part of the tambour frame, I have mounted supports 80, 81 which have suitable bearings for the several longitudinal shafts 80 and in addition I have provided a yoke 82, for supporting various working parts at one end of the tambour frame.

On the right end of each of the longitudinal shafts I have provided miter gears 83, 85 84, and 85 and arranged substantially vertical, and passing through the yoke 82, in which it journals, I provide a shaft 86 on which are arranged means for transmitting power from an external source to the longitudinal shafts. On the shaft 86, are arranged the three sleeves 87, 88, and 89, each of which carries a pair of miter gears 90, 91 and either of which is adapted to mesh with one of the miter gears 83, 84 or 85 on the respective longitudinal shafts 19, 20 and 21. Each of the sleeves is movable longitudinally on the shaft 86, and arms 92, are keyed on the shaft 86, and each has a key 93, which engages in a hole in the miter gears 90, so that each sleeve will be revolved with the shaft and still be movable along the shaft. The arrangement of the several pairs of gears 90, 91 is such that if the upper gear of either sleeve is thrown into mesh 95 with the gear of its corresponding shaft, the latter will be caused to revolve in one direction, while if the lower gear is thrown into mesh the shaft will be revolved in the reverse direction; and if the gears 90 and 91 100 are both out of mesh as shown in Fig. 2, the longitudinal shaft will remain idle. The several sleeves 87, 88 and 89 are controlled by three levers 94, 95 and 96, fulcrumed at 105 97, 98 and 99, upon the yoke; and the rocking of these levers will control the operations of the longitudinal shafts through the meshing of the several gears of the sleeves. The power for operating these several levers 94, 95 and 96 is preferably derived from the 110 shaft 86, itself. The shaft 86, is provided near its lower end with a worm 100, which, through a worm gear 101, revolves the shaft 102, carried upon the yoke, and upon this shaft the worm gear 101, is mounted. The 115 shaft 102, is therefore revolved whenever the shaft 86, revolves.

Upon the shaft 103, near the shaft 102, I have fulcrumed three levers 104, 105 and 106, side by side; and these levers are con- 120 125 130

ected by the rods 107, 108 and 109 respectively, with the levers 94, 95 and 96, through which connections the latter are operated. I have provided three cams for operating the three levers 104, 105, and 106, which cams are mounted on the shaft 102. Cam 110 shown in Fig. 9, operates through the engagement of the bowl 111 upon one arm 113, of the lever 104, in the cam groove 112, and thereby transmits the force through lever 104, rod 107 and lever 94, to the sleeve 87, for throwing either of the latter gears 90 or 91 into mesh with the gear 83, on shaft 19 or for throwing both gears out of mesh. 15 When the bowl is in either the part 112 or the part 115 of the groove of cam 110, the sleeve 87 will be in the position shown in Fig. 2, when both gears 90 and 91 will be out of mesh with gear 83, and the side 20 clamping mechanism will be idle. When the bowl 111, is in the part 116, of the cam groove the levers 104 and 94 will be rocked to such a position that the gear 90 will be in mesh with gear 83, and as a consequence 25 the shaft 19, will operate to turn the pin rollers so as to cause their pins to release the fabric. When the bowl is in the part 117, of the cam groove, the levers 104 and 94, will be rocked to such a position as will 30 throw the gear 91 into mesh with the gear 83. In consequence thereof the shaft 19 and therefore the pin rollers, will be revolved in a direction reverse to the first, and the pins of the pin roller will engage the 35 fabric and draw it taut.

The cam 118, performs the operations similar to those just described with relation to the levers 106, and 96, and sleeve 89, but the lengths of the rises and falls of the cam 40 race will be so proportioned as to properly time the movements of the levers so as to cause the results referred to hereinafter, in the description of the operation of the mechanisms.

45 The cam for operating the levers 105, and 95 which controls the movements of the fabric rollers, however, is somewhat different from cams 110 and 118 and is shown in Fig. 10. The bowl 119 of the lever 105 is 50 affected by the cam 120, in the following manner. Assuming the cam 120 to be revolving right hand in Fig. 10, while the bowl 119 is engaged by the concentric portion 121, of this cam, the levers 105 and 95, will be 55 in the position shown in Fig. 2, and gears 90 and 91, will both be out of mesh with the gear 84, and the middle horizontal shaft 20, and therefore the fabric roller will be idle. When the bowl 119, is engaged by the rise 60 122 of this cam, the lever 105, will be rocked to throw the levers 95, up and the gear 90, into mesh with gear 84 when the shaft 20 will operate the reeling shafts to cause the upper fabric roller of each pair to reel up 65 fabric from the lower roller. When the

bowl 119, is engaged by the outer wall 123 of the cam, the levers 105 and 95, will be rocked back until the bowl is engaged by the portion 124, when the gear 90, will be thrown out of mesh with the gear 84, and the reeling operation will be thus automatically stopped after a predetermined movement of the fabric rollers has taken place. The cam plate 125, is made adjustable, so that the time of the return movement of levers 105 and 95, can be adjusted according to the amount of movement to be imparted to the fabric rollers. By turning the thumb screws 126 the plate 125 can be moved in the arc of a circle the screws 126, traveling in slots 80 127 in the cam. The position of the plate 125 can thus be adjusted to bring the lever 105 back at any required time, to stop the movement of the fabric rollers after a predetermined amount of fabric has been reeled. 85

It may be that the operator will not in every instance determine, properly, in advance the amount of movement to be imparted to the fabric rollers, or that on account of seams or imperfections in the cloth 90 a greater or less amount is to be reeled up, and I have therefore provided means within the control of the operator for adjusting the movement to secure the desired results. The lever 95 which operates the sleeve 88, is 95 somewhat different from the levers 94 and 96. In this instance the arm 95, fulcrums from the stud 98 and the other arm 129 thereof forms a handle to be gripped by the operator. The arm 128 to which the rod 100 108 is directly fulcrumed, fulcrums on the stud 98. A clutch 130 is arranged to fulcrum on the pin 132, carried by the arm 129, and has a recess 131, which receives the pin 134, on the arm 128. The clutch 130 is held 105 in engagement with the pin 134 by a spring and when the clutch is thrown in, as shown in Fig. 2, the lever 95, is subject to the movements of the bar 108 and therefore is controlled by the operating cam 120. 110

Should the fabric rollers reel up too much, or not enough fabric, when the cam 120 makes its revolution, and it is desired to adjust the action, the operator grips the arm 129 and by pressing the handle 133, disengages the clutch from the pin 134, when the lever 95, can be rocked by hand. When thus disengaged, the lever 95, can be rocked and in consequence either the gear 90 or gear 91 can be thrown into mesh with the gear 84, and the fabric rollers thereby turned in either direction; and when the proper movement has taken place the lever 129—95 may be rocked to the intermediate position and both gears 90 and 91 will be out of 125 mesh. Upon releasing the handle 133, the clutch will reengage the pin 134 and the mechanism will again be subject to the automatic control of the cam 120.

I provide means for transmitting power 130

to the shaft 86, which in no way interferes with the free movement of the tambour frame.

As shown in Fig. 7, I preferably take my operating power from a counter shaft 135 mounted upon the ceiling or in any other suitable location; though any other source of power, may be utilized. Upon this shaft 135, I have provided a loose pulley 136 and a fast pulley 137 over which a belt (not shown) operates to revolve the counter shaft 135. By shifting the belt from one of these pulleys to the other the shaft 135, can be started or stopped, in well known manner. I have provided a belt shipper 138 for this purpose which is provided with a weight 139, and with a brake shoe 140, for engaging the fast pulley, to stop the shaft. A rod 141, is employed to operate the belt shipper and it extends down within reach of the operator. The shaft 135, is provided with a gear 142, which miteres with the gear 143, on a short shaft 144 directed downward. The latter shaft is connected by a universal joint 145 with a downward extending telescoping shaft, consisting of the part 146, which extends into the sockets 148, of the part 147 and has a groove 149 in which a pin 150 on the part 148 engages. The two parts of this shaft are adapted to telescope to allow for the movement of the tambour frame relative to the source of power. The end of the telescoping shaft is connected by a universal joint 151, with the shaft 86, and by this connection the operating force is transmitted to the various mechanisms on the tambour frame.

Upon the stud 152, on the yoke 82, I have fulcrumed a trigger 154, the upper end 155 of which engages, and is engaged by, a stop 156 carried by the starting and stopping rod 141. The end of this trigger is engaged by a pin 157 on the side of the worm gear 101, so that upon each revolution of the shaft 102, and its cams, the trigger 154, will be tripped to release the controlling rod 141, as will appear hereinafter; or it may be released by hand at any time the operator desires.

The operation of the device is as follows:

It is to be understood that the various branches of the mechanism could be operated by hand power.

Assuming the mechanisms to be in the condition shown in Fig. 1, which is the condition that exists while the embroidery is being worked upon the fabrics; at which time the fabrics are held taut between the fabric rollers and are held taut by the side clamps. The shaft 86, and consequently all the parts operated thereby are idle. If the fabric stretched between the fabric rollers has been embroidered on and it is desired to reel up enough fabric to present a new

piece before each row of needles, the plate 125, on cam 120 having been set to a position which will stop the fabric rollers when the desired amount of fabric has been reeled; the attendant will then pull down on the starting rod 141, to set the mechanism into operation. When the rod is drawn down the belt shipper will shift the belt to the fast pulley 137, on the counter shaft, when the latter will be set in motion. Through the gears 142, and 143, the telescoping shaft will be revolved and the telescoping shaft transmits the operating force to the shaft 86. The revolution of shaft 86, causes the sleeves 87, 88, and 89 with the attached bevel gears to revolve therewith; and through the worm 100, and worm gear 101, the shaft 102, which carries the cams 110, 118 and 120 is caused to revolve. Soon after the shaft 102, is started, the pin 157 on the side of the worm gear 101, moves from its engagement with the trigger 154, and the latter rocks, until its upper end 155, engages over the stop 156, on the starting rod 141, so that when the operator lets go of the latter, it will be held down by the trigger until the shaft 102, completes its revolution, when the pin 157, will trip the trigger and thereby release the starting rod, in consequence of which the weight on the belt shipper will rock the latter and cause the shifting of the belt and the stopping of the machine. It is during the revolution of the shaft 102, that the various operations are performed. When the shaft 102, is making its revolution the following takes place. The movement of cam 110, will cause its cam groove to act through the lever 104, and rod 107 to rock the lever 94. This will reciprocate the sleeve 87, causing either the gear 90 or the gear 91 of this sleeve to mesh with the gear 83 of the lower longitudinal shaft. Whether the gear 90 or 91, is thus thrown in will depend upon the direction of revolution of the shaft 86; but let it be assumed that the gear 90, is thrown in. This will cause shaft 19, to be revolved and in consequence of the gears 79, on this shaft and the gears 78, on shafts 71, the latter will be revolved and the pin rollers 66, will be turned back. The pins 68, will be withdrawn from the fabric as the pin roller is turned back and the comb 76 will tend to strip the fabric from the pins as the pin roller revolves. The movement of the shaft of the pin roller and the cam 72, carried thereon acts through the arm 73, to rock the shaft 64, which carries the grooved roller 62; and causes the latter to be moved away from the fabric, so as to leave the fabric free so far as the side clamps are concerned. The cam 110 now shifts the sleeve 87 to the intermediate position and discontinues the rotation of the longitudinal shaft. This operation takes place simultaneously at op-

posite ends of the machine, the pin rollers on the opposite ends of the machine revolving reverse to each other. The lateral stress being removed from the fabric the vertical stress is next released. The cam 118 will now act on the roller of lever 106 rocking the latter and the latter, through the rod 109, rocks the lever 96, and moves the sleeve 89, sufficiently to cause the gear 90, of this sleeve to mesh with the gear 85, of the uppermost longitudinal shaft, when the latter will be set in motion. The gears 54, on the longitudinal shaft 21, acting on the gears 52, on the shafts 47 will cause the latter to revolve.

The threads 46 of the shaft 47 will operate on the block 45, to move the rod 42, downwardly and as the arms 44, are carried on this rod they will be lowered and the worms 38, will move down therewith, when the lower rollers 25, will turn, under the tension of the fabric, sufficiently to relieve the fabric of the vertical stress. The same longitudinal shaft 21, operates through gears 60^a and 52^a, to turn the shaft 47, near the middle of the machine and the threads 46, thereof will act through the block 45 to lower the bar 59, on which the brackets 60 are carried. This releases the brackets 60 from the upper roller of each pair, so that the latter may be revolved. The cam 118, now shifts the sleeve 89 to the intermediate position and this part of the mechanism stops. The release of the tension upon the fabric caused by the movement of the rod 42, will permit the lower rollers to sag sufficiently to release them from contact with the brackets 56. The tension is now taken off the fabric and the brackets are free, so that the fabric is free to be reeled up. The cam 120 will act upon the lever 105, and through the rod 108, the lever 95, will be rocked to reciprocate the sleeve 88, and throw the gear 90 of this sleeve into mesh with the gear 84, of the intermediate longitudinal shaft, when the latter will be set in motion. The gears 31, of this shaft 20, acting on the gears 30, will revolve the shafts 29. The worms 32, and 38, revolve with the shafts 29 and they act respectively on the worm gears 33, and 39 to revolve the fabric rollers and reel the fabric from the lower to the upper rollers. The rollers 24, will be revolved faster than the rollers 25, because of the difference in the pitch of the worms 32, and 38, and if the circumference of the fabric on the upper roller is less than on the lower rollers there will be no slack cast in the fabric between the rollers. On the other hand, if the upper rollers draw too fast from the lower rollers a point will be reached where the stress of the fabric will overcome the effect of the friction caused by the springs 36 pressing the worms 32 against the collars 37; and the shaft 29 will slip in-

side the worms 32; and the shaft 29 and the upper rollers will lose motion until the lower rollers let off enough fabric to reduce the tension on the fabric; when the upper rollers may again turn. The fabric rollers 70 will stop when the desired amount of fabric has been reeled. When the plate 125, of the cam 120 comes into contact with the bowl of lever 105, the latter will be rocked back to its former position, the time of 75 which movement will depend upon the position of the plate 125. The rocking of lever 105, will operate through rod 108 to rock the lever 95 back to its former position, when the sleeve 88, will be moved until its gears 80 are no longer in mesh with the gear 84, of the horizontal shaft. The reeling movement of the fabric rollers has now ceased. If the operator observes the fabric at this time and finds that the fabric has been 85 reeled too much or not enough, he or she, takes hold of the handle 129 and releases the clutch from engagement with the pin 134. The lever, 95 can now be rocked by hand and if the handle 129 is moved down, 90 the sleeve 88, will be moved to throw its gear 91, into mesh with the gear 84, and the fabric will be reeled back until the handle 129 is returned to its intermediate position, when the reeling action will cease. Or if 95 the handle 129 is raised, the gear 90 will be thrown into mesh with gear 84, and the fabric will be reeled upwardly an additional amount. It is obvious that the reeling of the fabric is within the control of the operator and that the automatic device can be supplemented by the hand control. It will also be apparent that the mechanism may be operated through the hand control alone if desired. The fabric having been reeled, 100 a reversal of some of the movements will take place. The cam 118, now rocks the lever 106 in a direction reverse to its previous movement, actuating the rod 109, and lever 96, sufficiently to throw sleeve 89 which 105 has been in the intermediate position, so as to bring the gear 91 into mesh with the gear 85, of the shaft 21. The latter will now revolve in a direction reverse to its first movement, and a reversal of the shafts 47 will 110 cause the rods 42, to be drawn upwardly. This will return the worms 38 to their former positions and during their movement they will revolve the lower rollers 25 and 28, sufficient to place the final vertical stress 115 upon the fabric, which will be retained until the next reeling operation takes place. The reversal of shaft 21, also reversed the movement of the shaft 47, of the bracket device; and as a result the rod 59, will be 120 drawn upwardly, until the brackets 60, engage under the upper rollers and press against them sufficiently to prevent the fabric, or the weight of the rollers from 125 causing the latter to sag in the middle. 130

The pressure exerted by the brackets 60, will be determined by the spring 51^a. When sufficient pressure of the brackets has been attained, the friction of the collar 50^b against the gear 52^a, will be overcome, and if the shaft 47^a, continues to revolve the collar 50^b will slip against the gear 52^a, and the upward movement of the bar 59 will cease. I have shown these two movements as occurring simultaneous but this is not imperative. The cam 118 will now rock the levers 106, and 96 back to their intermediate or starting position, when the shaft 21, will remain idle. The cam 110 will now rock the lever 104, rod 107, and lever 94, from their normal or intermediate position in the reverse direction to their first movement, moving the sleeve 87 until the gear 90 is thrown into mesh with the gear 83, when shaft 19 will be reversed in its movement. This will reverse the direction of rotation of the shafts 71, and consequently the pin rollers 66 will be revolved in a direction reverse to their previous movement. The cams 72, will rock the shafts 64, bringing the grooved rollers 62, toward the pin rollers 66, and pressing the fabric between them. As the rollers 66 revolve the pins 68 will pass into the fabric and will travel through the grooves 70 of the rollers 62. The pin rollers will be revolved sufficiently to place the fabric under tension longitudinally of the machine, but provision is made for preventing too great a strain on the fabric. The roller 66 is loose on the shaft 71 being held between the collar 71^b and a coiled spring 71^a. If the strain on the fabric becomes too great, the pressure caused by the coiled spring 71^a against the roller 66 will be overcome, and the shaft 71 will turn in the pin roller which will not respond to the movement of shaft 71 beyond the desired limit. When the side clamps have been properly turned the cam 110 rocks the lever 104 rod 107 and lever 94 back to their intermediate positions, and the shaft 19 ceases to revolve. The shaft 102, has now made one complete revolution and as the pin 157 again comes into contact with the lower end of the trigger the latter will be rocked to release the rod 141 and the belt shipper will operate to stop the mechanisms.

The above operations may be repeated as often as required.

In some cases it may be desirable to disconnect the upper fabric rollers from the driving gear, so as to be able to turn them individually, for instance when new material has to be attached to the same; or again for the purpose of bringing the two rollers of a set into proper relation. In Fig. 15 I have shown means for accomplishing this. I have shown a block 127^a in the bracket 128^a on the tambour frame and which when in the position shown in

Fig. 15 is held by a cotter pin 129^a, so that the worm 32 and gear 33 are in mesh; the roller 24 being journaled in the block 127^a. When the pin 129^a is withdrawn, the block 127^a and with it the roller 24 may be moved 70 away from the worm, to disengage the gear 33 from the worm 32, when the roller may be revolved individually. The arrangement is the same at each end of the roller 24.

In some cases it may be desirable to operate the rollers for a longer period, for instance when putting new material on the rollers. For this purpose I disconnect the shaft 102 from the shaft 86 and in Fig. 14 I show means for doing this. A collar 130^a, is secured by a pin 131^a to the shaft 86 alongside the worm 100. On this collar is an extension 132^a which has a vertical aperture. An extension 137^a on the worm 100 has a like aperture. A pin 133^a is placed 85 through the apertures in the extensions 132^a and 137^a, so that the worm must revolve with the shaft 86. When it is desired to disconnect the parts, the pin 133^a is removed and is placed in an aperture of an extension 134^a at the other end of worm 100 and into an aperture 136^a in the yoke frame 82; so that the worm 100 will no longer revolve with the shaft but will be locked stationary and all the mechanism 90 connected with it will be held idle. Under this condition the fabric rollers may be caused to turn, if desired, upon releasing the clutch 130 and swinging the lever 133 upwardly or downwardly thereby throwing 100 either gear 90 or gear 91 of the sleeve 88 into mesh with the gear 84.

My invention makes it possible to perform all the operations incidental to the reeling of the fabric, by mechanical means, and in such relative order that there will be no conflict in the actions. In fact the operations are performed in the same order as they were formerly performed by manual labor. Furthermore, I have so constructed 110 my improvements that all danger of injuring or destroying the fabric are eliminated and the results are more uniform and satisfactory than heretofore.

By employing all the features of my invention it is possible to operate the mechanism automatically.

I believe my present invention to be a pioneer one, and while I have carefully described in detail, the various parts of the mechanism embodying my invention in the preferred form, I do not wish it to be inferred that the invention is limited to the construction herein shown and described, as many changes may be made without departing from the spirit of my invention or the scope of the claims herein. Furthermore, the various branches of my invention may be segregated and be separately used for the individual advantages to be obtained 130

therefrom, though I consider the use of the complete mechanism secures the greatest advantage. It may be also said that many of the elements which are employed in the present embodiment of my invention are in themselves new and claims will be made therefor.

Having described my invention, what I claim is:—

- 10 1. In an embroidering machine embodying fabric rollers arranged to receive the fabric one from the other, means for engaging the sides of the fabric and adapted to place the same under tension after it has been shifted, means including the rollers for shifting the fabric and tensioning the same after it has been shifted, and means for causing said operations to be performed in sequence.
- 15 2. In an embroidering machine embodying fabric rollers arranged to receive the fabric one from the other, means for engaging the sides of the fabric and adapted to place the same under tension, movable means for supporting the fabric rollers intermediate their ends, and means for reeling the fabric rollers, operating said side tension devices and moving said supporting devices in sequence.
- 20 3. In an embroidering machine embodying fabric rollers arranged to receive the fabric one from the other, clamps for the sides of the fabric, adapted to place the fabric under tension after shifting, and means for releasing said side clamps, revolving said rollers and operating said side clamps to place the fabric under tension, and adapted to automatically perform said operations in sequence.
- 25 4. In an embroidering machine a pair of fabric rollers, tension devices for engaging the sides of the fabric to place the same under tension, means for placing the fabric under tension between the fabric rollers, and mechanism adapted to release the side tension devices, release the device for creating a tension between the rollers, to reel a predetermined amount of fabric from one roller to the other, restore the stress on the fabric between the rollers and operate said side tension devices to place a stress on the fabric, all in the order here named.
- 30 5. In an embroidering machine embodying fabric rollers arranged to receive the fabric one from the other, clamps for the sides of the fabric, adapted to place the fabric under tension, movable brackets for supporting the fabric rollers intermediate their ends, and means for operating said devices in the following order, first to release said side clamps, and release the supporting brackets then to revolve the fabric rollers for the purpose of reeling the fabric, then to operate the side clamps and brackets, where-60 by the clamps will place the fabric under

tension and the brackets will engage the fabric rollers.

6. In an embroidering machine, fabric reeling mechanism comprising a pair of fabric rollers, means for revolving said rollers simultaneously, to reel the fabric, means for operating on said rollers to release the stress on the fabric before, and restore it after, the reeling operation, means for supporting the rollers intermediate their ends and means for withdrawing said intermediate support before the reeling operation and restoring it thereafter to cause the support of said rollers intermediate their ends.

7. In an embroidering machine embodying fabric rollers arranged to receive the fabric one from the other, worm gears and worms for the fabric rollers, clamps for the sides of the fabric, adapted to place the fabric under tension, movable brackets for supporting the fabric rollers intermediate their ends, and means for operating said devices, comprising means for releasing the side clamping devices and for throwing them in to draw the fabric taut, means for revolving said worms to reel the fabric, means for reciprocating a worm to place the fabric under tension between the rollers, and means for operating the supporting brackets to cause them to support the fabric rollers or to be released therefrom.

8. In an embroidering machine embodying fabric rollers arranged to receive the fabric one from the other, worm gears, and worms, for the fabric rollers, clamps for the sides of the fabric, adapted to place the fabric under tension, movable brackets for supporting the fabric rollers intermediate their ends, and means for operating said devices, in the following order, to wit, releasing the side clamps, reciprocating a worm gear to release the tension of the fabric between the rollers, moving the supporting brackets from the rollers, revolving the fabric rollers to reel the fabric, reciprocating a worm to place the fabric under tension between the rollers, and operating the side clamps to place the fabric between them under tension.

9. In an embroidering machine embodying fabric rollers arranged to receive the fabric one from the other, side clamps for placing a tension on the fabric and adapted to be thrown into and out of engagement with the fabric, means for operating said side clamps and means for automatically reversing the said operating means, and means for revolving the fabric rollers and adapted to be automatically operated when the side clamps are released.

10. In an embroidering machine embodying fabric rollers, a shaft for revolving said rollers, side clamps for the fabric, a shaft adapted to operate the side clamps to place a tension upon the fabric or release it therefrom, means for operating said latter shaft,

means for automatically causing the reversal of the operation of the clamping devices, means for operating said first shaft and means for automatically causing said operation while the side clamps are released.

11. In an embroidering machine embodying fabric rollers, a shaft for revolving said rollers, side clamps for the fabric, a shaft adapted to operate the side clamps to place a tension upon the fabric or release it therefrom, means for operating said latter shaft, means for automatically causing the reversal of the operation of the clamping devices, means for operating said first shaft, means for automatically determining the extent of operation thereof, and means for automatically causing the operation of the fabric rollers, while the side clamps are thrown out.

12. In an embroidering machine embodying fabric rollers, means for operating said rollers embodying a worm gear, a worm meshing therewith and a shaft, revoluble side clamps for placing a tension upon the fabric, means for operating the same, embodying a shaft, means for controlling the operations of said shaft, embodying cams adapted to effect the throwing into and out of operation of said first shaft and the reversal of said second shaft.

13. In an embroidering machine embodying fabric rollers, worm gears, worms, a shaft arranged longitudinally of the machine for operating said worms, revoluble side clamps for placing the fabric under tension, a shaft arranged longitudinally of the machine for operating the same, means for operating said shafts, reversing devices for said shafts, cams operated automatically with the operation of said shafts, and adapted to cause the reversal of said clamp operating shaft and the starting and stopping of the roller operating shaft.

14. In an embroidering machine embodying fabric rollers and means for operating the same, embodying worm gears and worms, a shaft arranged longitudinally of the machine for revolving said worms, movable supporting brackets for the rollers, revoluble side clamps for placing the fabric under tension, shafts arranged longitudinally of the machine for operating said brackets and side clamps, means for reciprocating a worm of the fabric roller operating device, to cause a tension on the fabric between the fabric rollers, a shaft for operating the same, means for operating said shafts, reversing devices for reversing the direction of rotation of said shafts, cams and means whereby said cams will cause the said second and third shafts to be reversed in their operation and cause the starting of the roller operating shaft while the side clamps are thrown out and the supporting brackets are released.

15. An embroidering machine embodying a tambour frame having reeling mechanism for the fabric, comprising a pair of fabric rollers, means for rotating said rollers simultaneously, and the receiving roller faster than the other, and yielding means adapted to automatically maintain the desired stress on the fabric during the reeling thereof.

16. An embroidering machine embodying a tambour frame having reeling mechanism for the fabric, comprising a pair of fabric rollers, means for rotating said rollers simultaneously and the receiving roller faster than the other, yielding means adapted to maintain the desired stress on the fabric during the reeling thereof, and means for relieving the tension before, and restoring it after, the reeling operation.

17. An embroidering machine embodying a tambour frame having a fabric reeling device embodying a pair of fabric rollers, gearing on each roller, means for operating the gears of each roller simultaneously, and adapted to revolve the receiving roller faster than the other roller, and yielding means for automatically regulating the stress on the fabric while it is being reeled from one roller to the other.

18. In an embroidering machine embodying a tambour frame, having fabric rollers, and means for operating on each end of the rollers to revolve them, comprising a common shaft disposed longitudinally of the tambour frame and means for applying the operating force of said shaft to the opposite ends of the rollers and adapted to revolve the rollers at a lesser speed than said shaft.

19. In an embroidering machine of the type set forth, a tambour frame having fabric rollers arranged to receive the fabric one from the other, means for revolving said rollers, comprising worm gears on the opposite ends of the rollers, an upright shaft at each end of the machine provided with worms adapted to operate the worm gears of the rollers, and a shaft arranged longitudinally of the machine for simultaneously operating both of said first shafts.

20. In an embroidering machine a tambour frame having fabric rollers arranged whereby the fabric may be wound from one roller upon the other, and means for operating the rollers, embodying worm gears by which the revolving force may be applied simultaneously to the opposite ends of each roller, worms for operating said worm gears, the gears and worms for one roller being arranged to rotate the receiving roller faster than the other roller and means for resistably permitting a roller to slip relative to its operating means.

21. In an embroidering machine a tambour frame, having fabric rollers arranged to receive the fabric one from the other, and

to support the fabric in an operative position, and means for revolving said rollers, comprising means for simultaneously revolving said rollers at different speeds and 5 means whereby one of said rollers may be allowed to slip independently of the revolution produced by the operating means.

22. In an embroidering machine a tambour frame having fabric rollers arranged 10 to receive the fabric one from the other, and means for revolving said rollers, comprising worm gears for each roller, a shaft and worms thereon, adapted to operate said worm gears, the worms and gears of one 15 roller being of different pitch from those of the other, whereby said rollers will be simultaneously revolved at different speeds, the worm of one roller being adapted to slip relative to its operating means and a 20 spring arranged to resist said slipping action.

23. In an embroidering machine a tambour frame having fabric rollers arranged to receive the fabric one from the other, means 25 for revolving said rollers, comprising worm gears, for each roller, a shaft, and worms thereon adapted to operate said worm gears, the worms and gears of one roller being of different pitch from those of the other, 30 whereby said rollers will be simultaneously revolved at different speeds, the worm of the faster roller being adapted to slip relative to its operating means and means for resisting said slipping action.

35 24. In an embroidering machine a tambour frame, embodying fabric rollers arranged to receive the fabric, one from the other, means for revolving said rollers to reel the fabric from one to the other, and other means for 40 revolving one of said rollers to place a tension upon, or remove it from, said fabric.

25. In an embroidering machine a tambour frame, embodying fabric rollers arranged to receive the fabric one from the other, means 45 for revolving said rollers to reel the fabric from one to the other, and other means for independently revolving a roller to place a tension upon, or remove it from said fabric.

26. In an embroidering machine a tambour 50 frame embodying fabric rollers arranged to receive the fabric, one from the other, means for revolving said rollers to reel the fabric from one upon the other, embodying worm gears for revolving the rollers, worms for 55 operating the worm gears, means for operating the worms and means for reciprocating a worm to place a tension upon the fabric.

27. In an embroidering machine a tambour frame embodying fabric rollers arranged to 60 receive the fabric, one from the other, means for revolving said rollers, to reel the fabric from one and upon the other, embodying worm gears for revolving the rollers, worms for 65 operating the worm gears, means for revolving the worm gears to revolve the

rollers synchronously; and means for reciprocating a worm, independently of its revolving operation, to place a tension upon the fabric.

28. In an embroidering machine, a pair of 70 fabric rollers, tension devices for engaging the sides of the fabric to place the same under tension, said fabric rollers and side tension devices operated from a source of power, means for automatically causing the shifting 75 of the fabric and the operation of the side tension devices in sequence and the shifting of a predetermined amount of fabric, and manually operated means for modifying the amount of fabric shifted. 80

29. In an embroidering machine a movable tambour frame, fabric rollers thereon arranged to support the fabric in position for embroidering and to receive the fabric one from the other, means for individually operating said rollers to shift the fabric from one to the other and adapted to be operated from a source of power, and adjustable means for automatically arresting the operation of the rollers, whereby they may be set 90 to shift a predetermined amount of fabric.

30. In an embroidering machine a tambour frame embodying fabric rollers arranged to support the fabric, and to receive the fabric one from the other, and means for operating 95 the rollers to reel the fabric, and adapted to be operated from a source of power, and adjustable means adapted to automatically arrest the operation of the rollers, whereby they may be set to reel a predetermined 100 amount of fabric, and manually operated means for throwing said rollers out of operation independently of said automatic means.

31. In an embroidering machine, a tambour frame, fabric rollers for supporting the 105 fabric, and adapted to receive the fabric one from the other, and means for operating said rollers, comprising worm gears by which the fabric rollers are each revolved, worms adapted to operate said worm gears, means 110 for operating said worms synchronously and means whereby a roller may be shifted away from the worm to disengage its worm gear from its operating worm.

32. In an embroidering machine embodying a movable tambour frame, rollers carried thereon, and arranged to receive the fabric one from the other, means carried on said tambour frame for revolving said rollers, a stationary support, a power driven shaft 120 thereon and a flexible power transmitting means for transmitting power to said roller operating means, while the tambour frame is in its various positions and without interfering with the movements of the tambour frame. 125

33. In an embroidering machine embodying a tambour frame and means for supporting the fabric on the tambour frame, means for holding the side edges of the 130

- fabric taut, embodying a revoluble member for each side edge of the fabric, having means for piercing the fabric, and means for revolving the said member and for causing them to engage and disengage the fabric.
34. In an embroidering machine embodying a tambour frame and means for supporting the fabric on the tambour frame, and side clamps for holding the side edges of the fabric taut, embodying revoluble members at each side of the fabric, adapted to engage the fabric between them, and means for revolving the revoluble members at one side of the fabric reversely and simultaneously to those at the other, for the purpose set forth.
35. In an embroidering machine embodying means for supporting a fabric, a tension device for the fabric embodying a roller having a row of fabric piercing elements adapted to engage the fabric when the roller is rotated in one direction and means for stripping the fabric from said fabric piercing elements when the roller is revolved in the opposite direction, and means for revolving said roller.
36. In an embroidering machine embodying a tambour frame and means for supporting the fabric on the tambour frame, and side clamps for holding the side edges of the fabric taut, embodying revoluble rollers near each side edge of the fabric adapted to engage on opposite surfaces of the fabric, one of said rollers having pins for piercing the fabric and the other having grooves into which said pins may enter, whereby said pins will be caused to pierce the fabric, and means for revolving said rollers.
37. In an embroidering machine embodying a tambour frame and means for supporting the fabric on the tambour frame, and side clamps for holding the side edges of the fabric taut, embodying revoluble rollers near each side edge of the fabric adapted to engage on opposite surfaces of the fabric, one of said rollers having pins projecting at an angle to its radius and the other having grooves into which said pins may enter, whereby said pins will be caused to pierce the fabric, means for stripping the fabric from said pins, and means for revolving the rollers.
38. In an embroidering machine embodying means for supporting a fabric, a tension device for the fabric embodying a roller provided with a row of fabric piercing projections, a second roller arranged on the opposite side of the fabric from said first roller, and having annular grooves corresponding to the positions of the projections of said first roller, said rollers being adapted to engage the fabric between them so that when one of the rollers is revolved the fabric will be drawn taut by friction, and when further rotated the said projections will pierce the fabric to hold it under tension.
39. In an embroidering machine embodying a tambour frame and means for supporting the fabric on the tambour frame, and side clamps for holding the side edges of the fabric taut, embodying revoluble rollers near each side edge of the fabric, adapted to engage on opposite surfaces of the fabric, one of said rollers having pins projecting at an angle to the radius thereof and the other having grooves into which said pins may enter, whereby said pins will be caused to pierce the fabric, a comb arranged to strip the fabric from said pins when the pin rollers are revolved in one direction, and means for revolving said pin rollers in directions reverse to each other, and to reverse the direction of revolution of said rollers.
40. In an embroidering machine a tambour frame and fabric rollers for supporting the fabric on the tambour frame, and side clamps for holding the side edges of the fabric taut, embodying revoluble rollers near each side edge of the fabric, and arranged on the needle side of the fabric, said rollers having pins for piercing the fabric, rollers on the shuttle side of the fabric having grooves to receive the pins of the said pin rollers and arranged between the fabric rollers, means for revolving said pin rollers and means for moving said grooved rollers toward and from the fabric.
41. In an embroidering machine embodying a tambour frame, and means for supporting the fabric on the tambour frame, and side clamps for holding the side edges of the fabric taut, embodying revoluble rollers having pins adapted to pierce near the side edges of the fabric, means for causing said pins to pierce the fabric and means for revolving said rollers, and resistible means interposed whereby the tension of the fabric may overcome the revolving action upon the rollers.
42. In an embroidering machine embodying a tambour frame and means for supporting the fabric on the tambour frame, and slide clamps for holding the side edges of the fabric taut, embodying revoluble rollers having pins adapted to pierce near the side edge of the fabric, means for causing said pins to pierce the fabric and means for revolving said rollers, and adjustable, resistible means interposed whereby the tension of the fabric between the said pin rollers may overcome the revolving action upon the said rollers.
43. In an embroidering machine embodying a tambour frame and means for supporting the fabric on the tambour frame, and

side clamps for holding the fabric taut, embodying shafts, rollers thereon, operated by said shafts, springs arranged to permit, but resist, the movements of the rollers relative 5 to their shafts, said rollers having pins arranged at an angle to the radius thereof, and adapted to pierce the fabric, grooved rollers arranged on the opposite face of the fabric from said pin rollers and adapted to 10 receive the pins thereof, shafts on which the grooved rollers are arranged to be carried whereby the said rollers may be moved toward and from said pin rollers, a cam on said first shaft adapted to oscillate said 15 second shaft, and means for operating said first shafts.

44. In an embroidering machine embodying a tambour frame, fabric supports for supporting the fabric on the tambour frame, 20 and means for engaging the fabric supports between their ends, comprising engaging members, means for operating them, and resistible means whereby the resistance of the fabric supports on said engaging means 25 may automatically overcome the operating action on said engaging members.

45. In an embroidering machine having a movable tambour frame, a plurality of fabric rollers carried thereby, a plurality of engaging 30 members for engaging the fabric rollers between their ends to hold them true, and common means for operating a plurality of said engaging means from a common source.

46. In an embroidering machine embodying a tambour frame, fabric rollers for supporting the fabric on the tambour frame, and means for supporting the said rollers between their ends, comprising supporting 40 brackets, means for raising said brackets, comprising a threaded shaft adapted to raise and lower said brackets, means for revolving said shaft and a spring adapted to resistibly cause said shaft to be operated by 45 its operating means.

47. An embroidering machine having fabric supporting members, a plurality of movable brackets for supporting the fabric supporting members intermediate their ends, 50 and operating means therefor, embodying an upright shaft for operating the brackets, and a shaft disposed longitudinally of the machine for operating the said upright shaft.

48. An embroidering machine having fabric supporting members, a plurality of movable brackets for supporting the fabric supporting members intermediate their ends, and common means for operating a 60 plurality of brackets.

49. An embroidering machine having fabric supporting members, a plurality of movable brackets for supporting the fabric supporting members intermediate their 65 ends, and common means adapted to be op-

erated from a source of power and to operate a plurality of said brackets.

50. In an embroidering machine, fabric supporting and shifting means, side tension devices, comprising means near each side of 70 the fabric consisting of coöperating means which press the fabric between them, and means for operating the side tension devices at both sides of the fabric and adapted to cause the side tension devices to engage and 75 disengage the fabric and to place the fabric between them under tension while said fabric shifting means is inoperative.

51. In an embroidering machine a tambour frame and means for holding a fabric 80 thereon and for shifting the fabric, and side tensioning means for the fabric, embodying a device for engaging the fabric, smoothing the fabric by drawing the same with slippable friction, securing the fabric under 85 tension, and releasing the fabric to permit of its free passage when being shifted.

52. In an embroidering machine a tambour frame, means for holding the fabric, and side tensioning means embodying fabric 90 engaging means adapted to smooth the fabric by drawing the same with slippable friction, and means for securing the fabric under tension.

53. In an embroidering machine a tambour frame, fabric holding means, and side tensioning means embodying means for engaging portions of the fabric while under unequal tension, drawing the fabric by slippable friction to equalize the tension of the 100 fabric, and means for securing the fabric under tension.

54. In an embroidering machine a tambour frame, fabric holding means, and side tensioning means, embodying means for engaging portions of the fabric while under unequal tension and drawing the fabric by slippable friction to equalize the tension of the fabric, and means for positively tensioning and securing the fabric when equally 110 tensioned.

55. In an embroidering machine embodying fabric shifting means, means for engaging the sides of the fabric and adapted to place the same under tension after it is shifted and means for operating the fabric transferring means and operating the side tension devices in sequence.

56. In an embroidering machine, fabric supports, engaging members for engaging the fabric supports intermediate their ends to hold the support true, common means for operating the engaging members and means for automatically terminating the movement of the engaging members.

57. In an embroidering machine, fabric supports, an engaging member for engaging a fabric support, means for operating said engaging member, and means for terminating the movement of the said engaging 130

member, and adapted to be controlled by the resistance to the operation of the engaging member.

58. In an embroidering machine, a movable tambour frame, fabric supporting members carried thereon and arranged to support the fabric in position for embroidering and adapted to receive the fabric one from the other, means for operating both the receiving and delivering members individually to shift the fabric, and means for determining the extent of the shifting of the fabric.

59. In an embroidering machine, fabric supporting and shifting means, side tension devices comprising means near each side of the fabric, each consisting of coöperating members which press the fabric between them, and common means for simultaneously 20 operating the side tension devices at both sides of the fabric and adapted to cause said side tension devices to engage and disengage the fabric and to place the fabric between them under tension while the fabric shifting 25 means is inoperative.

60. In an embroidering machine having a fabric frame, means for shifting the fabric, means for securing the fabric in a direction

at right angles to the shifting movement, said securing means having elements for 35 piercing the fabric, and means for causing the said piercing elements to engage and disengage the fabric.

61. In an embroidering machine having a tambour frame, means for supporting the 35 fabric for the embroidering operation, and side tension devices adapted to engage the fabric between them, and to cause a drawing action on the fabric to smooth and tension the same and means for piercing the 40 fabric to hold it in its tensioned condition.

62. In an embroidering machine, means for supporting a fabric for the embroidering operation, side tension devices for engaging the sides of the fabric and adapted 45 to exert a stretching action on the fabric, means for operating said side tension devices and means whereby the said side tension devices may independently affect the action of the operating means thereon. 50

Signed at the city, county, and State of New York this 30th day of June, 1911.

JOSEPH A. GROEBLI.
